(57) CLAIM

The ornamental design for the combination ceiling fan housing and light fixture, as shown and described.

DESCRIPTION

FIG. 1 is a top view of the combination ceiling fan housing and light fixture in accordance with my design;

FIG. 2 is a bottom view of the combination ceiling fan housing and light fixture in accordance with my design;

FIG. 3 is a side elevation view of the combination ceiling fan housing and light fixture in accordance with my design;

FIG. 4 is a front elevation view of the combination ceiling fan housing and light fixture in accordance with my design; and,

FIG. 5 is a perspective view of the combination ceiling fan housing and light fixture in accordance with my design.

The right and left elevational views are mirror images of each other.

The front and back elevational views are mirror images of each other.

The broken line showing of environmental structure in FIGS. 1-5 is for illustrative purposes only and forms no part of the claimed design.
